UNITED STATES PATENT OFFICE.

FRANK. DEARMIN, OF DE WITT, MISSOURI.

WELL BORING AND DRILLING MACHINE.

SPECIFICATION forming part of Letters Patent No. 295,621, dated March 25, 1884.

Application filed November 7, 1883. (No model.)

To all whom it may concern:

Be it known that I, F. DEARMIN, a citizen of the United States of America, residing at De Witt, in the county of Carroll and State of Missouri, have invented certain new and useful Improvements in Well Boring and Drilling Machines, of which the following is a specification, reference being had therein to the accompanying drawings.

10 My invention relates to an improvement in well-boring machines; and it consists in the frame A, having standards A' and A'', designed to furnish elevated bearings for pulleys A³, for carrying rope A⁴, platform B, actuating cog-wheel C, cylindric journal D, having flange D', disks or washers D³ and E, auger-holder C², shaft G, pinion H, guide-wheel a, cam-wheel h, having clutch b', clutch-wheel C', lever I, dog J, guides j, spring d', adjustable 15 shaft K, swivel L, reel M, auger R, spiral earth-elevator P, and in the combination and arrangement of the parts, substantially as hereinafter more fully shown and described.

In the drawings, Figure 1 is a side elevation. Fig. 2 is a plan on the line y y. Fig. 3 is a section on the line x x, Fig. 2. Fig. 4 is a plan detail of the bottom. Fig. 5 is a section on the line y y, Fig. 2. Fig. 6 is a detail showing the spiral earth-elevator, and Fig. 7 is a 20 detail plan view of the clutching and releasing mechanism.

In constructing the frame of my machine I project from frame A the inclined standard A' and bolt it at top to the coincident standards A'', the latter having pivoted therein the pulleys A³, and additionally strengthen the derrick thus formed by means of the knee-braces R, which are bolted thereto and to frame A. In the center of platform B is rigidly secured the cylindric vertical journal D, having cast integral therewith the flange D', which is bolted to the platform, the journal projecting through the circular opening D² in the center of the actuating cog-wheel C. A disk or washer, E, is rigidly secured to the under face of the actuating cog-wheel C, and it slides in practice upon flange D³. In the upper face of the actuating cog-wheel C is provided the notch e, for reception of the auger-holder C². The auger-holder C² has slot

C³ formed in its enlarged end or head, and also eye C⁴, by means of which and staple C⁵ it is secured to actuating cog-wheel C. The teeth of the actuating cog-wheel C mesh in the teeth of pinion H, which is rigidly secured to shaft G, which has its bearings in cross-bars f and B, and is provided with the guide-wheel a. The cam b, which has formed on its inner face a shoulder, b', is rigidly secured to shaft G. Its shoulder b' is designed to engage with a corresponding shoulder, d, provided on clutch-wheel C', which latter is rigidly secured to the end of a coincident longitudinally-adjustable shaft, K, having its bearings in the transverse bars h' and h². The shaft K is adjustable longitudinally, in order that clutch-wheel C', which is rigidly secured thereto, may alternately clutch against the shoulder b' and be released therefrom.

The operation is as follows: The machine is 70 operated by means of horse-power applied to the whiffletree-arm N of cog-wheel C, and this power is conveyed by means of the rigid pinion H to shaft G, which has rigidly secured thereto cam-wheel b, and cam-wheel b is provided with a shoulder, b', which engages with a corresponding shoulder, d, of clutch-wheel C', secured to the adjustable shaft K; hence the rotation of shaft K also causes the rotation of the fast reel M, to which the rope A⁴, being 75 secured, is wound thereon, and, as wound, elevates the auger until the cam projection of cam-wheel b, in performing its revolution, comes into contact with dog J, which it presses back against the lever I and spring d', and 80 thus throws clutch C' and its shaft K out of gear with cam-wheel b, and in thus releasing shaft K and its reel, auger C'' falls with great weight to the bottom of the well, and this action being performed the two shafts are again 85 thrown into gear by action of the spring d', and in and out of gear alternately. When it is desired to lift the earth from the well, the spiral elevator P is secured to the bottom of the auger, the lever I is pushed to one side to 90 disengage the gearing of the two shafts, and secured in the position shown in dotted lines, Fig. 2, by means of pin p, inserted in orifice p', and the auger-holder C² is caused to 95 clasps the hook or swivel L of the auger-holder, 100

in order that the auger may be revolved with the motion of the cog-wheel C.

Having described my invention, I claim—

1. A well-boring machine consisting of the cylindric vertical journal D, projecting through cog-wheel C, having notch e and arm N, auger-holder C², shafts G and K, cam-wheel b, engaging with clutch-wheel C', dog J, lever I, spring d', reel M, rope A⁴, auger C⁷, and the pulley-frame, substantially as shown and described.

2. The combination of the shafts G and K, operating in guides j, lever I, spring d', cam-wheel b, clutch-wheel C', and dog J, for alter-

nately clutching and disengaging, substantially as shown, and for the purpose described.

3. The combination of the shafts G and K, having guides j, lever I, spring d', cam-wheel b, clutch-wheel C', dog J, reel M, rope A⁴, guided by pulleys A³ and secured to auger C', and the driving mechanism, substantially as shown, and for the purpose described.

In testimony whereof I affix my signature in presence of two witnesses.

FRANK. DEARMIN.

Witnesses:

W. H. STUCKER,
H. C. MILES.
